UNITED STATES PATENT OFFICE.

GEORGE H. BERRY, OF SHELTON, CONNECTICUT, ASSIGNOR TO INTERNATIONAL SILVER COMPANY, OF MERIDEN, CONNECTICUT, A CORPORATION OF NEW JERSEY.

DESIGN FOR A BACK FOR BRUSHES, MIRRORS, AND SIMILAR TOILET ARTICLES.

No. 39,717.

Specification for Design.

Patented Dec. 22, 1908.

Application filed September 23, 1908. Serial No. 454,475. Term of patent 7 years.

To all whom it may concern:

Be it known that I, GEORGE H. BERRY, a citizen of the United States, residing at Shelton, in the county of Fairfield and State of Connecticut, have invented a new, original, and ornamental Design for a Back for Brushes, Mirrors, and Similar Toilet Articles, of which the following is a specification, reference being had to the accompanying drawings, forming a part thereof, and in which—

The back has a deep edge molding defining a main panel which bears the surface ornamentation shown.

I claim:

The ornamental design for a back for brushes, mirrors and similar toilet articles, as shown and described.

GEORGE H. BERRY.
